(57) **CLAIM**

The ornamental design for a display screen or portion thereof with animated graphical user interface for a cooking device, as shown and described.

DESCRIPTION

FIG. 1 is a front view of a display screen or portion thereof showing the first image of a sequence of the animated graphical user interface, according to a first embodiment of the invention;

FIG. 2 is a front view of the display screen or portion thereof showing the second image of the sequence of FIG. 1;

FIG. 3 is a front view of the display screen or portion thereof showing the third image of the sequence of FIG. 1;

FIG. 4 is a front view of the display screen or portion thereof showing the fourth image of the sequence of FIG. 1;

FIG. 5 is a front view of the display screen or portion thereof showing the fifth image of the sequence of FIG. 1;

FIG. 6 is a front view of a display screen or portion thereof showing the first image of the sequence of the animated graphical user interface, according to a second embodiment of the invention;

FIG. 7 is a front view of the display screen or portion thereof showing the second image of the sequence of FIG. 6;

FIG. 8 is a front view of the display screen or portion thereof showing the third image of the sequence of FIG. 6;

FIG. 9 is a front view of the display screen or portion thereof showing the fourth image of the sequence of FIG. 6; and,

FIG. 10 is a front view of the display screen or portion thereof showing the fifth image of the sequence of FIG. 6. The outer broken line rectangle showing the display screen, and all other broken lines showing portions of the graphical user interface, illustrate portions of the article of manufacture and form no part of the claimed design.

1 Claim, 10 Drawing Sheets
